UNITED STATES PATENT OFFICE

EARL H. TREVETT AND HARRY A. DAVIS, OF HOPEDALE, MASSACHUSETTS, ASSIGNEES
TO DRAPER CORPORATION, OF HOPEDALE, MASSACHUSETTS, A CORPORATION OF
MAINE

BRAKE FOR HIGH-SPEED WARPERS

Application filed January 24, 1930. Serial No. 422,989.

This invention relates to improvements in warpers and more particularly improvements in warpers which are run at high speed.

The principal object of the invention is to

5 provide effective braking mechanism operable gradually and smoothly to arrest the rotation of the warp beam quickly.

In high speed warping machines the heavy warp beam acquires a very considerable momentum when driven at a high speed and as it is driven by frictional engagement of the warps upon the beam with the driving cylinder, considerable overthrow is likely to occur when, upon the stoppage of the warper, when 10 a brake is applied in the usual manner to the shaft of the driving cylinder or to the cylinder itself.

One of the objects of the invention is to provide a brake acting directly upon the warp beam itself.

Another object of the invention is to provide a warp beam brake applicable to one or preferably both ends of the warp beam.

A further object of the invention is to provide a warp beam brake comprising a frictional disk or annulus detachably secured to the head of the warp beam to permit renewal when the friction surface becomes worn.

30 A further object of the invention is to provide a warp beam brake in which braking members are applied simultaneously and equally to both ends of the warp beam in a direction substantially parallel to the axis of the warp beam, thereby avoiding undesirable 35 end thrust upon either end of the warp beam.

A further object of the invention is to provide a warper in which the warp beam gudgeons are carried upon gudgeon blocks which are movable along preferably arcuate arms

40 extending forward of the driving cylinder with braking mechanism for the warp beam which will engage substantially the same annular frictional areas upon the end or ends of the warp beam irrespective of the position 45 of the gudgeon blocks as they are moved along the gudgeon-supporting arms.

A further object of the invention is to provide gudgeon blocks which are movable along the gudgeon-supporting arms with self-aligning bearings operable to maintain proper

alignment of the shafts, notwithstanding the strain imposed upon the gudgeons by the application of the respective brakes to the ends of the warp beam.

Another and most important object of the invention is to provide brakes acting conjointly upon the driving cylinder and upon the warp beam operable rapidly to arrest the rotation of both the cylinder and the warp beam without substantial slippage therebetween. 55

A further object of the invention is to provide a construction in which the brakes for the cylinder and the warp beam are conjointly actuated from the same source of power. 60

Another object of the invention is to provide a construction which will produce a conjoint action of the cylinder brake and the warp beam brake which will not require as close adjustment as independent braking mechanism applied respectively to the cylinder and to the warp beam. 70

These and other objects and features of the invention will more fully appear from the following description and the accompanying drawings and will be particularly pointed out in the claims. 75

In the drawings:

Fig. 1 is a side elevation of such parts of a warper as are required to show the embodiment of the present invention therein; 80

Fig. 2 is an enlarged detail view of a portion of the head of the warp beam and one form of break mechanism applicable thereto mounted upon the gudgeon-supporting arm; 85

Fig. 3 is a similar view of a modified form of brake mechanism;

Fig. 4 is a longitudinal sectional view of a gudgeon block showing a preferred form of self-aligning bearing; 90

Fig. 5 is a vertical central sectional view of the gudgeon block and self-aligning bearing.

As in usual constructions the warper comprises end frames 1 standing upon the floor 2. A shaft 3, mounted in suitable bearings in the end frames, extends transversely of the warper and is driven at a high speed in any suitable manner from a suitable source 100

of power. The shaft 3 supports and rotates a driving drum or cylinder 4 which may be of the usual type, but which preferably is provided with longitudinal corrugations to engage the warps on the beam.

The warp beam may be of any suitable type comprising a cylindrical barrel 5, and heads 6, and gudgeons 7. The barrel of the warp beam rests against the driving drum 10 and the warps 8 extend as usual from a creel or other supply, through drop wires 9 and other usual adjunctive devices over the roll 10 and are secured at their ends in any suitable manner to the barrel 5 of the warp beam. Consequently, as the driving cylinder 4 is rotated the frictional engagement of the drum with the beam barrel rotates the beam, winding the warp yarns thereon. The yarn mass on the warp beam therefore gradually increases in diameter until the beam is filled. Consequently also, the total weight of the beam and yarn mass likewise gradually increases. The total weight of the warp beam and the yarn wound upon the same is very considerable amounting in many instances to six or seven hundred pounds when the beam is filled, and the rapid rotation of the warp beam imparts to it a very considerable momentum.

Upon detection of the breakage of a warp the drop wires act through usual mechanism to actuate the stop mechanism and to knock off the latch which retains the brake mechanism in inoperative position and thereby permit a spring, which is connected to the brake lever as in usual constructions, to apply the brake.

As above stated, the present invention contemplates the provision of means for quickly arresting the rotation of the warp beam by means of a brake applied directly to one or preferably to both ends of the warp beam and which desirably is actuated conjointly with a brake applied to the driving cylinder. Both brakes desirably are actuated from the same source of power.

A preferred embodiment of the invention is illustrated herein as applied to a warper of the type disclosed in the application of Clare H. Draper and Earl H. Trevett, Serial Number 323,842, filed December 5, 1928. In that construction the gudgeons of the warp beam are journalled in gudgeon blocks which are slidably mounted upon and movable along gudgeon-supporting arms which extend forwardly of the driving cylinder and are of convexedly arcuate form. In that construction means are provided for preventing increase in the resultant pressure upon the driving drum due to the increase in the total weight of the beam and yarn as the yarn is wound upon the beam. Such mechanism desirably is employed in the present construction. It will, however, be understood that the present invention may be employed in

other types of warpers within the meaning and scope of the claims.

In the embodiment of the invention disclosed herein both end frames are of a similar character and the mechanism for supporting both ends of the warp beam are alike and similar braking mechanisms are provided for both ends of the driving cylinder and both ends of the warp beam, such braking mechanisms being actuated from a rock shaft having similar arms at both ends for actuating the brakes conjointly.

As illustrated herein internal brakes are provided for each end of the cylinder, such brakes comprising brake shoes 11 and 12 which are pivotally mounted at their lower ends upon studs 13 and 14 extending inwardly from brackets 15 which are mounted upon the end frames. The brake shoes 11 and 12 are provided with webs 16 and 17 having pivotal studs 18 and 19 to which are connected toggle links 20 and 21, the pivots 22, which form the knee of the toggle, having bosses 23 which are adjustably connected by links 24 to arms 25 of a rock shaft 26 which extends across the warper and is mounted in suitable bearings in the end frames of the warper.

The rock shaft 26 is provided with an actuating lever 27 the end of which is connected by a spring 28 to a depending boss 29 upon one of a pair of brackets 30 which are secured to the end frames and are provided with pivots which carry gudgeon-supporting arms upon which the warp beam is movably mounted.

Pedal levers 31, which are rigidly connected to the rock shaft 26, extend forwardly and are provided at their ends with a connecting pedal 32 which when depressed rocks the shaft 26 in a direction to move the end of the brake-actuating lever downwardly, thereby releasing the brake shoes 11 and 12 from engagement with the inner wall of the cylinder.

The usual means for locking the brakes out of engagement are provided and comprises a rod or latch 33 which is pivotally mounted at its lower end upon the brake lever 27 in proximity to the end thereof and extends vertically upwardly therefrom through a slot in a keeper 34 and is provided near its upper end with a shoulder 35 adapted when the brake-releasing lever is depressed by the pedal to engage beneath the keeper 34.

A rock shaft 36, operated by the usual detector mechanism (not shown), is provided with an arm 37 which, upon actuation of the rock shaft by the detector mechanism, engages the upper portion of the vertical rod 33 and forces the shoulder 35 thereof out of engagement with the keeper 34, thus permitting the spring 28 to raise the ends of the brake levers 27 and apply the brake. By

providing an internal brake for the cylinder arms are mounted and springs 60, which are the likelihood of lubricant dropping from interposed between the sections 59 and the other parts of the machine upon brake shoes, brackets 48, serve normally to withhold the thereby impairing their efficiency, is obviated.

The braking mechanism above described has been heretofore employed and in itself forms no part of the present invention, which relates primarily to means for applying an auxiliary brake to one or preferably both ends of the warp beam and which desirably is conjointly operable with the cylinder braking mechanism.

As heretofore described the gudgeon 7 of the warp beam is mounted in gudgeon blocks 38 which are slidably mounted upon the convex arcuate tracks 39 forming the end portions of gudgeon-supporting arms 40. The gudgeon-supporting arms are pivotally mounted upon stud shafts 41 extending inwardly from the brackets 30 and the rear ends of the gudgeon-supporting arms are provided with pivotally mounted blocks 42 having apertures provided with screw threaded walls which are engaged by screw threaded shafts 43 which are mounted in bearings in suitable brackets 44 secured to the end frames and are provided with beveled gears 45 which engage complementary beveled gears 46 upon a cross shaft 47 which is mounted in bearings in the brackets 44 and in the end frames and provided with square ends to receive a wrench. By rotating the shaft 47 the gudgeon-supporting arms are raised and lowered as desired to permit doffing of the beam or to raise a new beam into proper operative relation to the driving cylinder.

In the construction illustrated the brakes for the warp beam are mounted upon the arcuate portion of the gudgeon-supporting arms and comprise brackets 48 which are secured by bolts or screws to downwardly extending webs of the gudgeon-supporting arms. The brackets 48 are provided with bosses 49 having pivotal shafts 50 upon which are mounted brake arms 51 having curved offset portions 52, and end portions 53 extending in substantial parallelism with the outer faces of the heads 6 of the warper. Brake shoes 54, which may be provided with friction members 55 to engage the head of the warp beam, are pivotally mounted centrally of their width upon shafts 56 mounted in bosses in the end portions 53 of the brake arms, and spiral springs 57 and 58 are interposed between the brake shoes 54 and the end portions 53 of said arms at equal distances from the pivotal shaft 56. These springs, in conjunction with the pivot, are effective to equalize the pressure of different portions of the brake shoe area upon the warp beam head.

The opposite ends 59 of the brake arms 51 extend beyond the pivots 50 upon which said

arms are mounted and springs 60, which are interposed between the sections 59 and the brackets 48, serve normally to withhold the brakes from engagement with the heads of the warp beam.

The brackets 48 desirably are secured centrally of the arcuate portion of the gudgeon-supporting arm and the brake arms desirably extend substantially radially with respect to said arcuate portion so that the ends of the warp beam and which desirably are conjointly operable with the cylinder braking mechanism.

As heretofore described the gudgeon 7 of the warp beam is mounted in gudgeon blocks 38 which are slidably mounted upon the convex arcuate tracks 39 forming the end portions of gudgeon-supporting arms 40. The gudgeon-supporting arms are pivotally mounted upon stud shafts 41 extending inwardly from the brackets 30 and the rear ends of the gudgeon-supporting arms are provided with pivotally mounted blocks 42 having apertures provided with screw threaded walls which are engaged by screw threaded shafts 43 which are mounted in bearings in suitable brackets 44 secured to the end frames and are provided with beveled gears 45 which engage complementary beveled gears 46 upon a cross shaft 47 which is mounted in bearings in the brackets 44 and in the end frames and provided with square ends to receive a wrench. By rotating the shaft 47 the gudgeon-supporting arms are raised and lowered as desired to permit doffing of the beam or to raise a new beam into proper operative relation to the driving cylinder.

The outer surface of the curved portion 52 of each brake arm is curved to provide a suitable cam 61 which is adapted to be engaged by a cam follower preferably in the form of a roller 62 which is mounted upon the cylindrical portion 63 of an arm 64 of the bell crank lever which is pivotally mounted upon a stud shaft 65 extending outwardly from the bracket 48. The other arm 66 of the bell crank lever extends substantially vertically downwardly and has an enlarged end portion having an aperture 67. Rods 68 extend through the apertures 67 in the ends of the arms 66 of the bell crank levers and springs 69 are interposed between the arms 66 and collars 70 which are adjustably secured upon the ends of the arms by nuts 71. The opposite ends of the rods 68 are pivotally connected to arms 72 extending upwardly from the rock shaft 26.

In the operation of the brake mechanism, therefore, the release of the shoulder 35 of the rod 33 from engagement with the keeper 34 will permit the spring 28 to draw the brake-actuating lever 27 upwardly, thereby rocking the shaft 26, and in addition to applying the internal cylinder brake will, through the arms 72, move the rods 68 rearwardly longitudinally, thereby swinging the bell crank lever arms 66 about their pivots and causing the opposite arms 64 of said bell crank lever, which carry the cam followers 62, to move in a direction to engage the cams 61 upon the brake arms 51, and thereby force the brakes into engagement with the heads of the warp beam. Thus the cylinder brakes and warp beam brakes are actuated conjointly and by the same source of power.

By reason of this conjoint actuation of the cylinder brakes and the warp beam brakes from the same source of power the necessity of fine adjustments which would be required if the cylinder brake and warp beam brake were operated from independent sources of power are obviated.

Desirably the warp beam heads are pro-

vided with special frictional members to co-
operate with the brakes 54. As illustrated
herein such frictional members comprise
disks or flat annular plates 73 of fibre board,
leather, or other suitable material, which are
located in proximity to the periphery of the
warp beam heads and are detachably secured
thereto by screws 74, or other suitable fast-
ening means, the heads of which are coun-
tersunk below the surfaces which are engaged
by the friction members 55 of the brake shoes.
By reason of this construction wear upon
the heads of the warp beam is not only ob-
viated, but the friction members may be of
such character as to provide a greater degree
of friction than would be given by the usual
wooden warp beam heads. Furthermore,
these friction members can be readily re-
moved and replaced when worn, thus obvi-
ating also injury to warp beam heads which
would require their replacement after con-
siderable usage, in the absence of friction
members.

In Fig. 3 a modified brake construction
is illustrated in which the brake or brakes
are applied to the ends of the warp beam by
a spring or springs and are moved from and
held in removed position by positively actu-
ated mechanism. In this construction the
under face of the bracket block 48 is pro-
vided with a suitable recess which receives
the end portion of a powerful leaf spring 75,
and this end of the spring is fixedly clamped
between the bracket 48 and the gudgeon-sup-
porting arm. The leaf spring is curved out-
wardly to present a cam-like surface 76 and
then extends longitudinally in parallelism
with the brake arm a distance equal to or
somewhat greater than the path of move-
ment of the cam follower 62 upon the arm
64 of the bell crank lever. The leaf spring
is then curved inwardly into engagement
with the outer face of the end portion 53
of the brake arm and after extending along
the end portion is bent around the outer end
thereof to provide a hook 77 which engages
the inner face of the brake arm 51. In this
construction the leaf spring 75 acts to force
the brake into engagement with the heads of
the warp beam, but is normally held out of
engagement with the warp beam by the en-
gagement of the cam follower 62 with the
curved cam surface 76 of the spring.

In this construction the rods 68 are fixedly
secured to the arm 66 of the bell crank actu-
ating levers as these levers, when actuated
by depression of the pedal, move the cam
followers 62 into engagement with the curved
cam-like portion 76 of the spring, thereby
moving the springs outwardly to relieve the
pressure of the brakes upon the heads of the
drums. The curved end portion 77 of the
springs, which embraces the ends of the brake
arms, also serve positively to withdraw the

brakes from engagement with the heads of
the warp beam.

In view of the fact that the application of
the brakes to the heads of the warp beams
imposes considerable force upon the gud-
geons of the warp beam which may tend to
throw the axes of the gudgeons slightly out
of axial alinement, self-aligning bearings for
the gudgeons are provided which will main-
tain the bearings in effective alinement and
will also keep the heads of the warp beams
substantially in parallelism with the vertical
plane of the brake shoes.

In order to accomplish this purpose novel
gudgeon blocks are provided for supporting
the gudgeons of the warp beam.

A preferred gudgeon block construction is
illustrated in detail in Figs. 4 and 5. The
lower face of each gudgeon block 38 is pro-
vided with downwardly extending flanges 78
and 79 which extend below the track 39 upon
the gudgeon-supporting arm and a central
flange 80 extends downwardly through a slot
81 (see Fig. 2) in the arcuate curved portion
of the gudgeon-supporting arm 40. The cen-
tral flange 80 is also provided with an exten-
sion having at its lower end an aperture 82
for the connection of a chain 83 which may
lead to the mechanism for preventing increase
in resulting pressure on the driving drum
due to the increase in the total weight of the
beam and yarn as the yarn is wound upon the
beam as disclosed in the application of Dra-
per and Trevett above identified.

The gudgeon block 38 is formed in two
sections, the upper section 84 being pivotally
connected to the lower section by a pin 85 at
one side and provided with a bifurcated ex-
tension 86 adapted to be engaged by a lock-
ing pin 87 extending through a boss 88 pro-
jecting upwardly between the arms of the
bifurcated extension 86 from the lower sec-
tion of the gudgeon block.

The base of the gudgeon block 38 and the
upper section 84 are provided respectively
with spherically concaved surfaces 89 and
90 which receive a complementary spherical
surface 91 of a bearing 92, one end of which is
flush with the end of the gudgeon block, and
the other end of which terminates short of
the plane of the opposite end of the block. A
bushing sleeve 93, having a head 94, is mount-
ed within the spherical bearing 92 and is se-
cured thereto by screws 95, the head of the
sleeve desirably being flush with the end of
the gudgeon block. The gudgeon 7 is ro-
tatably mounted in the bushing sleeve 93.

The central portion of the bearing 92 is
cut away to provide an annular chamber 96
for a lubricant. A plurality of apertures
extend through the bushing 93 and wooden
plugs 97, having the grain extending longi-
tudinally of the plugs, provide means for
properly lubricating the gudgeon 7.

The bearing 92 is provided with radial apertures in alignment with the wooden plugs to permit the insertion of the plugs and also to provide means for introducing lubricant into the chamber 96. These apertures desirably are provided with tapered screw threaded walls and are closed by tapered screw threaded plugs 98. The upper section 84 of the bearing block is provided with an aperture 99 to permit the introduction of lubricant to the complementary bearing surfaces 90 and 91.

By reason of this construction proper lubrication of the bearing may at all times be maintained and the spherical bearings for the gudgeons will preserve self-alinement of the gudgeons at all times, thereby insuring parallelism of the planes of the friction surfaces upon the brake beam heads with the faces of the brakes, and also avoiding any tendency of wabbling of the brake beam during the warping operation.

It will be understood that although the invention is herein described as applied to the particular form of warper disclosed in the application of Draper and Trevett above identified, it is also applicable to other types of warpers, particularly high speed warpers, and that the invention broadly includes the provision of a warp beam brake alone or supplemental to a similar brake of any character, and further that while in the preferred embodiment of the invention the warp beam brakes are applied simultaneously to both ends of the warp beams in a direction parallel to the axis of the warp beam, a single warp beam brake may be employed, or other types of warp beam brakes may be used. It will, therefore, be understood that the particular embodiment of the invention disclosed herein is of an illustrative character and is not restrictive of the scope and meaning of the claims.

Having thus described the invention, what is claimed as new, and desired to be secured by Letters Patent, is:

1. A warper comprising a driving cylinder, a warp beam driven thereby, and having a head, said beam being mounted for bodily movement relative to said cylinder, a brake for said warp beam, and means for applying said brake to the head of said warp beam.

2. A warper comprising a driving cylinder, a warp beam driven thereby, and having a head at each end thereof, said beam being mounted for bodily movement relative to said cylinder, a brake for each head of said warp beam, and means for simultaneously applying said brakes to the respective heads of said warp beam.

3. A warper comprising a driving cylinder, a warp beam having heads located beyond the respective ends of said cylinder, said beams being mounted for bodily movement relative to said cylinder, a brake for

said warp beam, and means for moving the same in a direction substantially parallel with the axis of said warp beam into engagement with the head of said warp beam.

4. A warper comprising a driving cylinder, a warp beam having heads located beyond the respective ends of said driving cylinder, said beam being mounted for bodily movement relative to said cylinder, an annular friction disk detachably secured to one of said heads, a brake located in co-operative relation to said disk, and means for moving said brake into engagement with said disk.

5. A warper comprising a driving cylinder, a warp beam having heads located beyond the respective ends of said driving cylinder, said beam being mounted for bodily movement relative to said cylinder, brakes at each end of said warp beam, and means for moving said brakes simultaneously in a direction substantially parallel with the axis of said warp beam into engagement with the respective heads of said warp beam.

6. A warper comprising a driving cylinder, a warp beam having heads located beyond the respective ends of said cylinder, said beam being mounted for bodily movement relative to said cylinder, flat annular friction disks detachably secured to the respective heads and having their peripheries lying in proximity to the peripheries of said heads, brakes at each end of said warp beam, and means for moving the same simultaneously into engagement with said friction disks.

7. A warper comprising a driving cylinder, a warp beam having heads and gudgeons, a pair of arcuate gudgeon-supporting arms extending forward of said cylinder, a pair of gudgeon blocks supporting said beam gudgeons and movable along said arms as the yarn is wound upon the beam by frictional engagement of the cylinder therewith, a brake carried by one of said gudgeon-supporting arms, and means for applying said brake to the adjacent head of the warp beam.

8. A warper comprising a driving cylinder, a warp beam having heads and gudgeons, a pair of arcuate gudgeon-supporting arms extending forward of said cylinder, a pair of gudgeon blocks supporting said beam gudgeons and movable along said arms as the yarn is wound upon the beam by frictional engagement of the cylinder therewith, brakes carried by the respective gudgeon-supporting arms, and means for applying said brakes simultaneously to the respective ends of the warp beam in a direction substantially parallel with the axis of said warp beam.

9. A warper comprising a driving cylinder, a warp beam having heads and gudgeons, a pair of arcuate gudgeon-supporting arms extending forward of said cylinder, a pair of gudgeon blocks supporting said beam

gudgeons and movable along said arms as the yarn is wound upon the beam by frictional engagement of the cylinder therewith, a brake arm pivotally mounted upon one of said gudgeon-supporting arms having a brake positioned to move into engagement with substantially the same circular area of said warp beam irrespective of the position of the gudgeon blocks, and means for actuating said brake.

10. A warper comprising a driving cylinder, a warp beam having heads and gudgeons, a pair of arcuate gudgeon-supporting arms extending forward of said cylinder, a pair of gudgeon blocks supporting said beam gudgeons and movable along said arms as the yarn is wound upon the beam by frictional engagement of the cylinder therewith, a brake arm pivotally mounted on one of said gudgeon-supporting arms having a pivotally mounted brake movable into engagement with the adjacent head of said warp beam, resilient means intermediate of said brake arm and said brake operable to equalize the pressure of different portions of the surface area of said brake upon said head, and means for applying said brake.

11. A warper comprising a driving cylinder, a warp beam having heads and gudgeons, a pair of arcuate gudgeon-supporting arms extending forward of said cylinder, a pair of gudgeon blocks supporting said beam gudgeons and movable along said arms as the yarn is wound upon the beam by frictional engagement of the cylinder therewith, a brake arm pivotally mounted on one of said gudgeon-supporting arms having a pivotally mounted brake movable into engagement with the adjacent head of said warp beam, resilient means acting on said brake arm normally holding said brake out of engagement with the warp beam head, and means including a cam and a relatively movable cam follower operable to apply said brake to the head of said warp beam.

12. A warper comprising a driving cylinder, a warp beam having heads and gudgeons, a pair of arcuate gudgeon-supporting arms extending forward of said cylinder, a pair of gudgeon blocks supporting said beam gudgeons and movable along said arms as the yarn is wound upon the beam by frictional engagement of the cylinder therewith, a brake arm pivotally mounted on said gudgeon-supporting arm provided with a cam face and having a brake positioned to engage the adjacent head of the warp beam, a lever having means to engage said cam, and means for actuating said lever to cause the same to move the brake into engagement with the head of the warp beam.

13. A warper comprising a driving cylinder, a warp beam driven thereby, a brake for said cylinder, a brake for said warp beam,

and means operable conjointly to apply said cylinder brake and said warp beam brake.

14. A warper comprising a driving cylinder, a warp beam driven thereby, a brake for said cylinder, a brake for said warp beam, and means operable conjointly by the same source of power to apply said cylinder brake and said warp beam brake.

15. A warper comprising a driving cylinder, a warp beam driven thereby having heads located beyond the respective ends of said cylinder, an internal brake for said cylinder, a brake movable into engagement with one of the heads of said warp beam, and means operable by the same source of power conjointly to apply said cylinder brake and said warp beam brake.

16. A warper comprising a driving cylinder, a warp beam driven thereby having heads located beyond the respective ends of said cylinder, an internal brake for said cylinder, a brake movable into engagement with one of the heads of said warp beam, and means for conjointly actuating said brakes including a spring actuated lever, and means operable thereby conjointly to apply said cylinder brake and said warp beam brake.

17. A warper comprising a driving cylinder, a warp beam driven thereby having head located beyond the respective ends of said cylinder, internal brakes at each end of said cylinder, brakes movable into engagement with each of the heads of said warp beam, a rock shaft having arms operable respectively to apply the cylinder brakes and the warp beam brakes at both ends of the cylinder and warp beam conjointly, and spring actuated means for rotating said rock shaft.

18. A warper comprising side frames, a driving cylinder, a warp beam having heads and gudgeons, a pair of gudgeon-supporting arms pivotally mounted on said side frames and extending forward of said cylinder, a pair of gudgeon blocks supporting said beam gudgeons and movable along said gudgeon-supporting arms as the yarn is wound upon the beam by frictional engagement of the cylinder therewith, brackets mounted on said gudgeon-supporting arms, brake arms pivotally mounted on said brackets presenting cam faces and having pivotally secured adjacent their ends brake shoes movable into and out of engagement with the heads of said drums, resilient means normally holding said brakes out of engagement with said drum heads, levers pivotally mounted on said brackets having cam followers movable in parallelism with the planes of said heads to engage the cams upon said brake arms, a rock shaft pivotally mounted in said frame having arms yieldably connected to said brake levers, and means for actuating said rock shaft including a spring actuated arm, a pedal connected to said rock shaft operable to impose

5 a tension upon said actuating spring, and a detent connected to said brake actuating arm adapted to be released by the detector mechanism of the warper and thereby to permit said spring to apply the brakes.

10 19. A warper comprising a driving cylinder, a warp beam having heads and gudgeons, a pair of gudgeon-supporting arms extending forwardly of the cylinder, a pair of gudgeon blocks movable along the arms as the yarn is wound upon the beam by frictional engagement with the warps thereof, a brake mounted on one of said gudgeon-supporting arms operable to engage the head 15 of the warp beam, and self-aligning bearings in said gudgeon blocks for said gudgeons operable to compensate the tendency of distortion of the gudgeons from axial alinement upon application of the brake.

20 20. A warper comprising a driving cylinder, a warp beam having heads and gudgeons, a pair of gudgeon-supporting arms extending forwardly of the cylinder, a pair of gudgeon blocks movable along the arms as the 25 yarn is wound upon the beam by frictional engagement with the warps thereof, a brake mounted on one of said gudgeon-supporting arms operable to engage the head of the warp beam, and spherical bearing members in said 30 gudgeon blocks to receive said gudgeons, lubricant reservoirs in said gudgeon blocks, and means for transmitting lubricant from said reservoirs to said gudgeons.

35 In testimony whereof, we have signed our names to this specification.

EARL H. TREVETT.
